UNITED STATES PATENT OFFICE.

JOHN K. ROGERS, OF BROOKLINE, MASSACHUSETTS.

DESIGN FOR PRINTING-TYPE.

SPECIFICATION forming part of Design No. 13,278, dated August 29, 1882.

Application filed July 13, 1882. Term of patent 7 years.

To all whom it may concern:

Be it known that I, JOHN K. ROGERS, a citizen of the United States, residing at Brookline, in the county of Norfolk and State of Massachusetts, have invented and produced a new and original Design for a Font of Printing-Types, of which the following is a specification.

The types composing this font consist of an alphabet of capitals and lower-case letters, of the Roman form and of extra condensed charac-

ter, with figures, dollar-mark, and points. The accompanying impression taken from the types themselves shows their exact form.

I claim—
The design for types as described and shown.

JOHN K. ROGERS.
